UNITED STATES PATENT OFFICE.

JOHN WILKINSON, OF SYRACUSE, NEW YORK, ASSIGNOR TO H. H. FRANKLIN MANUFACTURING COMPANY, OF SYRACUSE, NEW YORK, A CORPORATION OF NEW YORK.

INTERNAL-COMBUSTION ENGINE.

1,371,405.

Specification of Letters Patent. Patented Mar. 15, 1921.

Application filed April 5, 1917. Serial No. 159,973.

To all whom it may concern:

Be it known that I, JOHN WILKINSON, a citizen of the United States, and a resident of Syracuse, in the county of Onondaga and 5 State of New York, have invented a certain new and useful Internal-Combustion Engine, of which the following is a specification.

This invention relates to air cooled internal combustion engines and has for its 10 object a particularly simple and efficient construction whereby the heat radiating or cooling surface is increased and whereby the cylinders can be cast in block and also 15 formed of a lighter material, as aluminum, than is now used, and the invention consists in the novel features and in the combinations and constructions hereinafter set forth and claimed.

20 In describing this invention, reference is had to the accompanying drawings in which like characters designate corresponding parts in all the views.

Figure 1 is a vertical cross sectional view 25 through the cylinder and the crank casing of my engine, the piston, crank shaft and other moving parts being removed.

Fig. 2 is a fragmentary side elevation thereof, moving parts being omitted.

30 Fig. 3 is a plan view of parts seen in Fig. 2, one of the cylinders being shown in transverse section.

This internal combustion engine comprises, generally, a cylinder having an integral base portion or extension at the lower 35 end of its cylindrical wall and cooling flanges on the cylinder wall and on the base portion.

In this embodiment of my invention, the 40 crank case is divided transversely into upper and lower sections and the upper section is the base portion formed integral with the cylinder wall.

1 designates the cylinder wall; 2, the base 45 portion formed integral with the cylinder wall at the lower end thereof and constituting the upper section of the transversely divided crank casing.

3 is the lower section of the crank casing, which is secured to the section 2 in any suitable manner as by cap screws 4 extending through horizontal flanges 5, 6 provided respectively on the upper and lower sections 50 of the crank casing.

The line of division of the crank casing

extends transversely through the crank 55 shaft bearing 7, dividing said bearing.

The upper section 2 which is integral with the cylinder wall 1 is also formed with cam shaft bearings 8. 9 are vertical cooling flanges provided on the lateral sides of the 60 cylinders, and 10 are vertical flanges provided on the base portion 2, the flanges 10 forming continuations of some of the flanges 9.

Some of the flanges on the right hand 65 portion of the engine base 2, that is, the portion on which the cam shaft and the valve rods are located, are omitted.

When the engine is multi-cylinder, a plurality of cylinders and the base portions 2 70 thereof are cast in block, as seen in Figs. 2 and 3, and the cylinders are spaced apart on the base portion 2, and flanges or webs 12 connect the cylinders near the points where they are closest together. As here 75 shown, the cylinders are connected by two webs or flanges 12, these webs or flanges being provided with openings 13 at their lower ends for permitting the passage of air from the space between them.

The cylinders, the upper portion of the base and the webs connecting the cylinders are all cast in one piece, making a light rigid construction, so that a light metal can be used in the construction of the engine.

14 designates the head of each cylinder which is secured thereto in any suitable manner as by cap screws 15, this head being provided with suitable inlet and exhaust passages 16, 17 and with external laterally 90 extending heat radiating flanges 18 which are usually arranged in vertical alinement with the flanges 9 of the cylinder.

In use, the cylinders 1 are inclosed in casings formed in halves, the halves being located on opposite sides of the engine so that each cylinder is practically inclosed in a cylindrical casing or chimney, and the halves of the casing are secured to the flanges 12 by fastening members extending into the 95 openings 19 in said flanges. The air is moved downwardly through the casings over the cylinders and the base 2, usually, by means of a fly-wheel fan at the rear of the engine or a blower in front.

Owing to the section 2 forming an integral extension of the cylinder walls, the heat is conducted or distributed over a larger

area than when the cylinders are separably mounted upon a base, as it is well known that in engine construction, heat does not effectively conduct from one part to another which are joined together, and are not integral. Further, as before pointed out, a particularly rigid construction is provided which permits the use of a lighter construction than has heretofore been used in air cooled engine construction.

The arrangement of the casing of the cylinders and the air cooling system of the cylinders constitute the subject matter of another application.

15. What I claim is:

1. An internal combustion engine having its cylinder provided with integral base extensions at the lower end of its cylindrical wall and on opposite sides of the engine, the 20 cylindrical wall and the extensions being formed with heat radiating flanges, substantially as and for the purpose described.

2. In an air cooled multi-cylinder internal combustion engine, the combination of a plurality of cylinders having a base portion at the lower ends of their cylindrical walls, the cylinders being spaced apart on the base portion and having peripheral heat radiating flanges and webs extending lengthwise of 30 the cylinders and connecting the cylinders, the cylinders, base portion and webs being in block, substantially as and for the purpose described.

3. An internal combustion engine having the cylinder and the upper part of its crank case integral, and cooling flanges on the cylinder and said part of the crank case, substantially as and for the purpose specified.

4. An internal combustion engine having 40 its cylinder and contiguous portion of the crank case integral, cooling flanges extending lengthwise of the cylinder, and cooling flanges on said crank case forming continuations of the flanges on the cylinder, substantially as and for the purpose set forth.

5. An air cooled internal combustion engine having its crank case divided transversely into upper and lower sections, a cylinder integral with the upper section, and 50 cooling flanges provided on the cylinder wall and the upper part of the crank case, substantially as and for the purpose specified.

6. An internal combustion engine having its base divided transversely into upper and

lower sections, a cylinder integral with the upper section, and vertical cooling flanges on the cylinder wall and the upper part of the base, substantially as and for the purpose set forth.

7. An internal combustion engine having 60 its base divided transversely through the crank shaft bearings into upper and lower sections, means for securing the sections together, and a cylinder formed integral with the upper section, the cylinder having a removable head, the cylinder wall and the upper section of the crank case integral therewith, being provided with vertical cooling flanges, substantially as and for the purpose specified.

8. An air cooled multi-cylinder internal combustion engine having its cylinders cast in block and spaced apart throughout the height of the cylinders and provided with integral external flanges connecting the 75 cylinders and extending across the space between the cylinders; the flanges extending vertically lengthwise of the cylinders, the cylinders also having peripheral heat radiating flanges around the same, substantially as 80 and for the purpose specified.

9. An air cooled multi-cylinder internal combustion engine having an upper portion in its crank case and the cylinders cast in block, the cylinders being spaced apart on 85 the crank case and having integral flanges extending lengthwise thereof and connecting the same at the points said cylinders are nearest together, the cylinders also having heat radiating flanges around the same, substantially as and for the purpose set forth.

10. A multi-cylinder internal combustion engine having the upper portion of its crank case and the cylinders cast in block, the cylinders being spaced apart on the upper 95 portion of the crank case, integral flanges connecting the cylinders at the points they are nearest together, the cylinders and the upper portion of the crank case also having vertically extending flanges on their sides, 100 substantially as and for the purpose described.

In testimony whereof, I have hereunto signed my name, at Syracuse, in the county of Onondaga, and State of New York, this 105 29th day of March, 1917.

JOHN WILKINSON.
